(57) **CLAIM**

We claim the ornamental design for a lamp, as shown and described.

DESCRIPTION

FIG. 1 is a front view showing an embodiment of our new design for a lamp;
FIG. 2 is a right side view showing our new design shown in FIG. 1;
FIG. 3 is a left side view showing our new design shown in FIG. 1;
FIG. 4 is a back view showing our new design shown in FIG. 1;
FIG. 5 is a top view showing our new design shown in FIG. 1;
FIG. 6 is a bottom view showing our new design shown in FIG. 1;
FIG. 7 is a top perspective view showing our new design shown in FIG. 1; and,
FIG. 8 is a bottom perspective view showing our new design shown in FIG. 1.
The portions shown in broken lines are not part of the claimed design but show the environment in which the design is associated.
